(57) **CLAIM**

The ornamental design for a magnetic collar weight, as shown and described.

DESCRIPTION

FIG. 1 is a frontal perspective view of a magnetic collar weight showing my new design;

FIG. 2 is a top plan view of the magnetic collar weight as shown in FIG. 1;

FIG. 3 is a bottom plan view of the magnetic collar weight as shown in FIG. 1;

FIG. 4 is a front elevation view of the magnetic collar weight as shown in FIG. 1;

FIG. 5 is a rear elevation view of the magnetic collar weight as shown in FIG. 1;

FIG. 6 is a left elevation view of the magnetic collar weight as shown in FIG. 1;

FIG. 7 is a right elevation view of the magnetic collar weight as shown in FIG. 1;

FIG. 8 is a frontal perspective view of the magnetic collar weight shown in FIG. 1 attached to a shirt collar;

FIG. 9 is a top perspective view of the magnetic collar weight of FIG. 1 magnetically attached to a shirt collar;

FIG. 10 is a top plan view of the magnetic collar weight shown in FIG. 1 attached to the top side of a shirt collar;

FIG. 11 is a top plan view of the magnetic collar weight shown in FIG. 1 attached to the bottom side of a shirt collar;

FIG. 12 is a front elevation view of the magnetic collar weight shown in FIG. 1 attached to a shirt collar;

FIG. 13 is a rear elevation view of the magnetic collar weight shown in FIG. 1 attached to a shirt collar;

FIG. 14 is a left elevation view of the magnetic collar weight shown in FIG. 1 attached to a shirt collar; and,

FIG. 15 is a right elevation view of the magnetic collar weight shown in FIG. 1 attached to a shirt collar.

The broken lines showing the drawing disclosure are for illustrative purposes only and form no part of the claimed design.
